FIG. 24

PER ATTORNEYS

UNITED STATES PATENT OFFICE.

VIRGIL C. HARKRADER, OF PEORIA, ILLINOIS.

FOOTBALL GAME.

Application filed March 30, 1927. Serial No. 179,420.

This invention relates to football games.

One of the objects of the invention is in the provision of a football game that is adapted to be played by opposing players or 5 opposing sides, said game being governed as to the results of play by chance, there being included, however, such possibility of selection by contestants as to formation and play as would be exactly comparable to the 10 play in a regular football game, wherein the most skillful choice of formation and play would result, under ordinary circumstances, in a win by said contestant.

Another object is in the provision of a 15 football game that may be played by contestants in exactly the same manner as a regular football game, whereby the result may be gauged almost directly by the choice of formation and play, the contestant utilizing the 20 wisest selection, under ordinary circumstances being the winner.

Still another object is in the provision of a 25 football game that compares as to play exactly as that in a regular football game, and whereby the contestants may utilize the same selection of formation and play as in a field game, the results of the play following said choice being controlled by chance.

A further object is in the provision of a 30 football game which is adapted to be played in substantially exactly the same manner as a regular football game, leaving the control of each situation in the hands of the contestants, the results of each situation following 35 a choice of formation and play being determined by the spinning of an arrow or some chance mechanism, whereby the only element of luck that enters into the game may be directly comparable with the element 40 of luck that attends each play in a regular game.

A still further object lies in the provision 45 of a football game wherein a plurality of keys have been compiled by experts to cover substantially every result that might follow the use of the combined formations and plays covered by said keys, and chance means for indicating the results of play under such key.

An additional object lies in the provision 50 of a football game wherein a plurality of keys have been compiled covering the results that would naturally follow a choice of formation and play by offense and formation by defense, said keys being compiled by football 55 experts and being the result of careful con-

sideration and comparison with football statistics.

Yet another object is in the provision of a football game that has been worked out as respects results of plays following choice 60 of formation and play in such manner that same may be instructive as well as entertaining to those skilled or unskilled in football play.

Other objects will appear in the following specification taken in connection with the annexed drawings, in which—

Fig. 1 is a diagram of a football field, laid out in the manner required by the football regulations;

Fig. 2 is a plan view of a register for indicating the choice of formation and play;

Fig. 3 is a plan view of a chance dial and indicating arrow;

Fig. 4 is an index disclosing the combinations indicated by the register and location of keys;

Fig. 5 is an index of formations by offense and defense, and possible selection of play;

Fig. 6 is an explanation of abbreviations 80 utilized in the keys;

Figs. 7 to 24 indicate the keys or possible combinations that may result from a choice by offense of formation and play and a choice of formation by defense.

Before referring particularly to the drawings, it might be stated that the present football game differs entirely from any football games that have apparently been devised heretofore, in view of the fact that the present game includes a compilation of data as respects the possible results of play under a given condition, said compilation forming the results of study and comparison of a great number of football games. This compilation of 90 results has been worked out to such a degree as to substantially eliminate the element of luck from said game to any extent other than to the extent such element of luck is evident in a regular football game. In other words, in a 95 regular game, the element of luck enters into the result of the play. To make the point more clear, it might be said that in substantially every football situation there may be

a wise selection of formation and play by offense and a wise selection of formation by defense. If there is a wise selection of formation and play by offense, and an unwise selection of defensive formation, there is obviously a greater possibility of success in the play. 110

This illustrates exactly the present football game, inasmuch as the possibility of success in the play is comparable directly with the skill in selection of formation and play as well as selection of defensive formation. The plays which have been found to be most consistent ground gainers in college football, with due regard to the opponents' defensive formation, have been worked out on the charts to give similar results. Of course, it is not known in advance what the result of a play will be, but a wise choice will place the results within a certain range of limits (keys), after which the exact result is obtained within these limits by chance upon the wheel.

The present game has been worked out for statistical data in a manner to substantially prevent the possibility of a win by a contestant utilizing an unwise selection of play, and as a matter of fact, placing a premium upon a wise selection of play and a penalty upon an unwise selection. As a matter of fact, this is exactly what happens in a regular football game, and a strong or skillful team ordinarily has an advantage over a weaker team. The only chance in an ordinary football game for a weaker team to be successful is in the choice of play, and in the present instance, there is an advantage on the part of the most skillful player. However, the element of luck enters into the present game, just as in a regular football game, inasmuch as the play is governed in this instance by the spinning of an arrow.

No one can determine the results of a play in an actual football game until same has occurred. In the present game, the spinning of the arrow determines the result of play. So far as the results of the play are concerned, there is substantially the same range of results in the present game as there would be in a regular football game. These results, as far as this game is concerned, are called keys, each key governing the results of practically all, if not all, of the situations that might arise in a football game played under existing football rules and including the change of rules as made lately.

It is apparent that the present game might be readily changed to conform to any later rules that might be made in football play.

As respects the game itself, it is not thought necessary to designate by numerals the parts of figures that appear in the drawings, inasmuch as each sheet is readily susceptible of description without the necessity of minutely describing each portion.

For instance, Fig. 1 discloses in diagram a football field 2 laid out upon a base 1. This field is laid out in the manner covered by football rules, the same being one hundred yards in length and having the regular five yard markings 5. The goal posts 3 are indicated ten yards behind the goal line 4, in accord-

ance with the late change in the rules, which in the past required the goal posts to be placed directly upon the goal lines. In this figure, there are a series of holes 7 indicating each of the hundred yards on the field, said holes being fashioned to receive some sort of a marker to indicate the position of the ball on the field during play. There are similar holes 8 upon one side of the field, which permit the insertion of some sort of marker to indicate the yards to be gained by the contestant having the ball in his possession.

Fig. 2 is a register, the whole of which is indicated by 20 of the choice of formation 9 and play 10 by the offense or side holding the ball, the choice of defensive formation 11, the quarter 12, and the number of plays 13 and 14. The discs 9—11 are shown in the upper part of Figure 2 as they appear when removed from the register. Likewise, discs 12—14 are shown in the lower part of the figure. Each is mounted on a shaft 15, and may be rotated to any desired position by the players to expose a numeral in the window 16 cut in the face of 20. This register is moved before each play to first indicate the choice of formation by offense, second, the choice of formation by defense, and third, the choice of play by offense. It will be noted on the register that the play immediately follows the formation by the offense. However, this arrangement on the register is merely to simplify the arrangement of the keys that are covered by the combination of numbers that appear on this register. In other words, that part of the register indicating the play might just as well be where the defense formation is described, but for the purpose of simplifying the keys later to be described, and arrangement thereof, the register for the key is placed second in the combination rather than third, although the choice of play comes third when the selections are made.

Before starting play, or when any quarter is finished, that part of the register indicating the quarter is moved to indicate the quarter in which the game is played, namely, 1, 2, 3, and 4. Similarly, that part of the register indicating the number of plays, the same being designated in the proper manner, is moved following the combination of each play to a new number. Conforming to football rules, the football game is played in quarters and halves, respectively as to time, or by the number of plays. For purposes of simplifying the present game, the same is played by choosing a number of plays, and this choice may be either the regulation number covered by regular football rules, or may be some arbitrary number chosen by contestants playing the game.

Fig. 3 discloses a dial 17 and spinning arrow 15 mounted on a shaft 16, said dial being marked off with numbers as at 18 up to one hundred. At the base of each number

there appears various colors as at 19. Although various colors are shown, only a minority have any actual effect upon the results of play indicated by the spinning of the arrow, and these colors indicate penalties. Obviously, the penalties arise by choice, and as a matter of fact, substantially in the same manner that they arise in a regular football game. They cannot be anticipated and usually arise when least expected or when least wanted. Further, with respect to these colors, twenty five of the hundred numbers are designated in red as at 19. In order to encourage conservative football and penalize the taking of unnecessary chances, if the arrow stops on any of these twenty-five colors, when a line plunge or end run has been attempted on the fourth down, irrespective of the result of the gain made, such gain is cut down one foot. The obvious result of this penalty would be that if a line plunge or end run were attempted on the fourth down and the offense merely made its required yardage, this yardage would be cut down one foot, and therefore the ball would go to the other side.

Again, with respect to the colors, there are two of the numbers designated in black, which penalize the offensive side when attempting either a passing play, line plunge or end run in territory between the said offensive team's own goal line and the twenty yard line. The penalty of attempting such plays when obviously the team should kick out of danger is a fumble recovered by opponent.

The purple colors penalize an offensive side five yards and the green colors penalize the defensive team five yards.

One number is designated in brown, to indicate a fifteen yard penalty on offensive side, and one in blue to indicate a fifteen yard penalty on defensive side.

There are two green and two purple colors, lying adjacent the numbers, these colors having significance only in case of a certain situation in football which may be explained as follows: Under certain circumstances, during a football game, it may be a strategic move by the defense to elect a fair catch. This is an exceptional circumstance in a game and necessitates another spinning of the dial to determine whether the catch is made. Ordinarily, of course, one spinning of the dial is sufficient for one complete play, with the exception of the kickoff, or the return of any punt. When the arrow is spun, in order to indicate the results of the fair catch, following election thereof, if the arrow stops on one of the green or purple colors, this signifies that a fumble has been made by the defensive man receiving the kick, but that said man attempting the catch recovered the ball. It might be stated also that if the arrow stopped on the black number, this would sig-

nify that a fumble had been recovered by the kicking team. In either case, however, play is carried on as if no fair catch was signalled for, that is, of course, in case the arrow should have stopped at either of these penalizing numbers.

Fig. 4 is an index, disclosing the combinations indicated by the register, and the page, or place, in an accompanying pamphlet in which the keys are located. Fig. 4 also has disposed below the index the location of keys covering free kicks, there being some situations which merely call for a single choice of play by the offensive team, and thereafter the spinning of the arrow to indicate the results. These occasions are covered by this index, the same all relating to kicks which are made from formations indicated therein.

Fig. 5 is an index of possible formations by offense, formations by defense and plays by offense. These formations and plays cover generally all formations and plays known at this time, and coming within the present football rules. It is obvious, however, that these formations and plays might readily be changed, either now, or later, to accord with any change in football rules.

It might be well to state that in this description of applicant's present football game, it is assumed that the game of football is so well known, also the rules governing same, as to obviate any necessity of discoursing on same to any extent whatsoever. It is possible that the layman might not have a detail knowledge of all of the possible plays, but the present game is devised to permit a player having any knowledge whatsoever of football to play same and to increase his knowledge of the game during such play. The game contemplates substantially all, if not all, of the situations that might arise under football rules, and is therefore adapted to be played by either football experts or by any ordinary player.

Fig. 6 is an explanation of abbreviations utilized in the keys. It is not thought necessary to go into a detailed description of these abbreviations as they are obvious, and in case there is an abbreviation in one of the keys, it is merely necessary for the player to turn to this list of abbreviations in order to find just what same means. It may be assumed that a contestant, after playing for a short time, will soon commit these abbreviations to memory.

Figs. 7 to 24 inclusive indicate the keys, which are the results of the combinations indicated by the register, said keys determining the possible result of every distinct situation that would arise following the selection of play.

With respect to the manner of playing the game, there may either be two sides composed of one player on either side, or perhaps better, two sides with others acting as officials

in exactly the same manner as regular football is played, and in the manner covered by football rules. When sides have been chosen, and the number of plays for the full game have been decided upon the contestants, either by chance or by agreement, decide who will kick off, this being the first play in the football game. The kick is made under regulation football rules, from the kicker's own forty yard line. The arrow is then spun to indicate the result of the kick-off. The kick-off does not count for a complete single play, but it is necessary to spin the arrow again, in order to determine either how far the ball was returned after the kick-off or more specifically, the result of play following the receiving of the kick. The kick-off and receiving of the kick count as one play and are so indicated on the register indicating the number of plays.

It is apparent, also, that the kicker, who was the offense for one play, thereafter becomes the defending side and the side receiving the kick becomes the offense. Play is then resumed and the selection of plays is made in the manner before described, and the results indicated also in the manner described.

Before describing the actual play, as contemplated by this game, it might be well to reiterate that the present game differs from other football games, in that there is a possibility of selection, or judgment by either side, irrespective of the situation, in just exactly the same manner as there would be in an ordinary football game, the result of play being merely left to chance, as it would be in a regular football game. For instance, in case of a deliberate safety, which is contemplated by the football rules, the offensive side can call for a deliberate safety and register the desired number of plays before the safety, so long as he does not exceed the number of plays to which he is entitled in that sequence of downs. Further, in case of forward passes, where the result indicated by the keys, following a spinning of the arrow, shows same to have been intercepted, the defense contestant may decline interception and have the play treated as an incompletely passed, if he so desires. Still further, respecting this possibility of selection that might arise under any football situation, in case of penalties, there is the option, under certain circumstances, of accepting the penalty or accepting the gain.

Applicant feels that with the above description, and with the complete disclosure in the drawings, anyone having even a slight knowledge of football, might readily play in an intelligent manner the present game. As a matter of fact, after completing but a few plays, it will be found that the actual play is very simple as well as very enjoyable and instructive. However, to even more fully

explain the operation of the game, one quarter will be described in exactly the same manner as same would be played by two contestants, which will be designated A and B. It is thought that the description of play of one quarter will suffice, as the other quarters would be played in the same manner. As stated before, any number of plays might be agreed upon between the contestants, irrespective of football rules.

Before the kick-off is made, the dial on the indicator marked "Quarter" is moved in such manner that the numeral 1 appears, and the dials containing the markings "Formation", "Play", and "Defense" are prepared for movement as soon as the play is called.

In the first instance, the arrow is spun for the kick-off by contestant B, coming to a stop at numeral 8. Thereupon, turning to the key governing the kick-off, it is found that the numeral 8 indicates that the ball has traveled forty-five yards from the contestant B's forty yard line, from which point the kick-off was made. The ball is received upon the fifteen yard line of contestant A, whereupon the arrow is spun by A, in order to determine the number of yards that the ball is returned by said contestant.

The kick-off and return of the kick is indicated as one play, and therefore the dial on the indicator referring to the number of plays is moved so that the numeral 1 appears, indicating that one play has been made.

Upon the spinning of the arrow by contestant A, it is found that the arrow points to numeral 28, and referring to the key for the return of the kick-off, it is found that numeral 28 indicates that the ball was returned by contestant A five yards, whereupon the ball is put in scrimmage by contestant A, on his twenty yard line.

The ball is now in contestant A's possession, and he chooses formation 1, contestant B chooses defense formation 2, and contestant A chooses play No. 1. When these selections are duly registered (see Fig. 2), the indicator discs 9, 10 and 11 shows a combination of 112. The arrow is now spun by contestant A and stops at the numeral 47, whereupon, upon consulting key 112, it is found that numeral 47 indicates that there was no gain, the ball therefore remaining in the possession of contestant A on the twenty yard line, it being second down and still ten yards to go. The dials on the indicator are again moved to indicate that two plays have been completed.

Contestant A now chooses formation No. 1, contestant B chooses defense formation No. 2 and contestant A chooses play No. 1. When these selections are duly registered, the indicator shows the combination 112, whereupon the arrow is spun, stopping at numeral 68. Key 112 is then referred to and numeral 68 is found to indicate that a gain of ten yards was made.

It will be noted that numeral sixty eight also indicates a color hazard, the color being green, and by turning to the key for the color hazards (see Fig. 6), it will be found that a 5 five yard penalty was inflicted on the defensive team. By his play, contestant A made a gain of ten yards, and because of the color hazard, a five yard penalty was inflicted on contestant B, therefore there remains the option to contestant A to choose either the 10 penalty or the results of the play, and in this instance, of course, the result of the play is taken, and the ball is now on the thirty yard line in the possession of contestant A, ten 15 yards having been made, and it now being first down and ten yards to go. The indicator is moved to indicate that three plays have been completed.

Contestant A again chooses offensive formation 1, contestant B chooses defense formation 1 and contestant A play 2. When these selections have been duly registered, the indicator shows that the combination for the play is 121. The arrow is spun, stopping at numeral 25 58, and upon referring to the key, it is found that numeral 58 indicates that one yard was lost. The ball is moved back to the twenty 50 nine yard line in the territory of contestant B, and the indicator is moved to show that four plays have been made.

It being second down and 11 yards to go, contestant A chooses formation 2, contestant B chooses defense 2 and contestant A play 2, or an end run. When these selections have 35 been duly registered upon the indicator, they show the combination 222. The arrow is spun by contestant A and same stops at numeral 92. Turning to the key 222, it is found that a twenty five yard gain was made. 40 The ball is now in the possession of contestant A on contestant B's forty six yard line, it being again first down and ten yards to go. The number of plays now registered is five.

Contestant A now chooses formation 2, contestant B defense formation 1, and contestant B play No. 2. When these selections have been registered on the indicator, they show the combination 221. The arrow is spun and stops at numeral 38. Turning to key 221, it 45 is noted that numeral 38 indicates a twelve yard gain, whereupon the ball is moved to B's thirty four yard line, it being again first down and ten yards to go. The register is changed to indicate that six plays have been 50 made.

Contestant A chooses formation 1, contestant B uses defense 1, and contestant A play 2, or an end run. These selections having been made, the indicator registers combination 121. The arrow is spun, stops at 55 numeral 36, and turning to the key 121, it is found that numeral 36 indicates that a one yard gain was made, the ball now being on B's thirty three yard line, it being second down and nine yards to go. The register is

turned to indicate that seven plays have been made.

Contestant A now chooses formation 1, contestant B defense 1 and contestant A play 1. When these selections have been duly registered, the indicator shows the combination to be 111, and the arrow is spun, stopping at numeral 58. Turning to key 111, it is found that numeral 58 indicates a twelve yard gain, whereupon the ball is moved to B's twenty 70 one yard line, it being first down and ten yards to go. The register is changed to indicate that eight plays have been completed.

Contestant A now chooses formation 1, contestant B defense 1, and contestant A 80 play 1, or a line plunge. This selection still shows combination 111 and the arrow is spun, stopping at numeral 77. Turning to key 111, it is found that numeral 77 indicates no gain. It is now 85 second down and still ten yards to go, the register having been changed to indicate that nine plays have been made.

Contestant A, finding that the line plunge has not resulted in gain, chooses formation 2, 90 contestant B defense 1, and contestant A play 4, or medium length pass. When these selections have been registered, the indicator shows combination 241, the arrow is spun and stops at numeral 14. When key 241 has been referred to, it is found that numeral 14 indicates a completed pass of thirteen yards, after which the receiver runs for an additional three yards, making in all, a sixteen 95 yard gain. The ball is now on B's five yard line, it being first down and goal to go. The second dial indicating the number of plays is moved to show that ten plays have been completed.

Contestant A now chooses formation 1, 105 contestant B defense 4, and A play No. 1. When these selections have been duly registered, the indicator shows combination 114. The arrow is now spun and stops at 12, whereupon key 114 is referred to and it is found that numeral 12 indicates no gain. It is now second down and goal to go. The play register is moved to indicate eleven completed plays.

Contestant A again chooses formation 1, 115 B defense 4 and A line plunge or play 1. The same combination 114 appears on the register, and the arrow is spun, stopping at numeral 21. Upon referring to key 114, it is found that numeral 21 indicates a one yard gain. The ball is now on B's four yard line, it being three down and goal to gain. The register indicates twelve plays completed.

Contestant A, still believing that a line 120 plunge will result in a touchdown, again chooses formation 1, contestant B defense 4 and contestant A play 1, or a line plunge. The same combination 114, is again registered, and when the arrow is spun, it stops at numeral 45, whereupon, referring to key 125

114, it is found that numeral 45 indicates a two yard gain, the ball now being on B's two yard line, it being fourth down and goal to gain. The register is now turned to indicate that thirteen plays have been completed.

5 Inasmuch as it is fourth down and two yards to go, and contestant A, finding that line plunges are apparently ineffective, now chooses formation 1, B chooses defense formation 4 and A chooses play 3, or short pass from three to eight yards. When these selections have been duly registered, the indicator shows the play combination to be 134. The arrow is spun, stopping at numeral 50, and turning to key 134B, it is found that numeral 50 indicates an incompleted pass of four yards, the ball going over the goal line. The ball is now brought out to the twenty yard line in compliance with the rules governing 10 a touchdown, and placed in scrimmage by contestant B, who now assumes the offensive. The register is then turned to indicate that fifteen plays have been completed.

Contestant B chooses formation 2, A 25 chooses defense formation 2 and B play 2. When these selections have been duly registered, the indicator shows combination 222. The arrow is spun, stopping at numeral 4, and when 222 is consulted it is found that numeral 4 indicates no gain, the ball remaining on the twenty yard line in possession of contestant B, it being second down and ten yards to go. The register is duly moved to indicate fifteen completed plays.

35 Contestant B now chooses formation 2, contestant A defense formation 2 and B play 5. When these selections have been duly registered, the indicator shows combination 252. The arrow having been spun and stopping at 40 68, key 252 is consulted, and it is found that numeral 68 indicates that a pass of thirty five yards was intercepted and that the interceptor ran fifteen yards in the direction of its opponent's goal. This places the ball in the 45 possession of contestant A on B's forty yard line. The ball is now placed in scrimmage by A, it being first down and ten yards to go. The register is moved to indicate that sixteen plays have been completed.

50 Contestant A chooses formation 1, B chooses defense formation 1 and A chooses play 5, the same being a long pass. When the selections have been duly registered, the indicator shows a combination of 151. The arrow 55 is now spun, stopping at 5. When the key 151 is referred to, it is found that numeral 5 indicates a completed pass of thirty five yards. The ball is now in A's possession on B's five yard line, it being first down and goal 60 to gain. The register is now changed to indicate seventeen completed plays.

Contestant A now chooses formation 1, B defense formation 4 and A play 1, which selections, when duly registered, show on the 65 indicator the combination 114. The arrow

is spun, stopping at numeral 60. Upon referring to key 141, numeral 60 is found to indicate a six yard gain, and therefore a touchdown. The register is now changed to indicate eighteen completed plays.

70 In conformity with the official football rules, the ball is brought out to the three yard line and contestant A now has the option of kicking from the three yard line through the goal posts, which are located ten yards beyond the goal line, or of rushing the ball by any play he chooses over the goal line, the same being three yards away. In this instance, the contestant A chooses formation 3, B defense formation 4 and A a place kick, 80 or play No. 8.

When these selections have been duly registered, the indicator shows combination 384. When the arrow has been spun, it stops at numeral 81, and when key 384, for kicks made 85 from one to five yard line, is referred to, it is found that the kick was successful, the score now being 7 to nothing in favor of contestant A. The register is now changed to indicate that nineteen plays have been completed.

90 B now has his choice of kicking or receiving, and in this instance chooses to kick. The ball is placed on B's forty yard line, the arrow spun, stopping at 1, and upon reference to the key, it is found that a sixty five yard kick has been made, carrying the ball over the goal line. It is therefore optional on the part of A whether the ball shall be brought out and put into play on the twenty yard line or whether he shall attempt to run it back. In this case he downs the ball behind his goal line. The register is now turned to indicate that twenty plays have been made.

95 What I claim is:

100 1. A foot ball game comprising a plurality of keys covering results compiled from statistical data and with due regard to averages and hazards of plays that might be attempted under foot ball rules, a register for arriving at the combination disclosing the proper key, said register recording the choice of offense formation, the choice of defense formation and the play by offense, and means controlling by chance the results of each play.

115 2. A foot ball game comprising a plurality of keys covering possible results of plays that might be attempted under foot ball rules, an indicator showing the choice of formation and play by offense and the formation by defense, thereby registering the proper key showing possible results of play and a dial controlling by chance the results of play.

120 3. A foot ball game comprising a plurality of keys covering results of plays that might be attempted under foot ball rules, an indicator showing choice of formation and play by offense and formation by defense, means controlling by chance the results of each play as 125 130

same may appear under the proper key and a diagram laid off to represent a foot ball field.

4. A foot ball game comprising a plurality of keys covering the possible results of plays that might be attempted from any formation or situation under foot ball rules, and means for arriving at the proper key following a choice of formation and play by offense and 10 a choice of formation by defense.

5. A foot ball game comprising a plurality of keys covering the results of plays that might be attempted from any formation or situation under foot ball rules, means for 15 arriving at the proper key following a choice of play by the offense and choice of play by the defense, and chance mechanism indicating the result of play covered by the indicated key.

20 6. A foot ball game comprising a plurality of keys covering the results of plays that might be attempted from any formation or situation under foot ball rules, means for arriving at the proper key following choice of 25 formation and play by offense, chance mechanism indicating the result of play covered by the indicated key and a diagram of a foot ball field, including means for indicating the position of the ball thereon at all times.

30 7. A foot ball game including a plurality of keys covering the results of plays that might be attempted from any formation or situation under foot ball rules, an indicator 35 registering the choice of formation and play by offense, chance mechanism indicating the result of play covered by said key, said chance mechanism including means for indicating possible penalties.

40 8. A foot ball game including a plurality of keys covering the results of plays that might be attempted from any formation or situation under foot ball rules, a register indicating the proper key following a choice

of formation and play, an index for quickly finding said key, chance mechanism controlling the results of said play as indicated by the proper key, and a diagram of a foot ball field, including means for indicating the position of the ball at all times. 45

9. A foot ball game comprising a plurality of keys covering the results of plays that might be attempted from any formation or situation under foot ball rules, means for indicating possible formations and plays, means for registering the combinations of formation and play, chance means for controlling the results of play under such combination and an index for quickly finding the proper key disclosing the results of play as indicated by the chance mechanism. 50 55 60

10. A foot ball game comprising a plurality of keys covering the results of plays that might be attempted from any formation or situation under foot ball rules, and a register for arriving at the proper key following a choice of formation and play, said register including a dial indicating the formation chosen by offense, a second dial indicating the formation chosen by defense and a third dial indicating the choice of play by offense. 65 70

11. A foot ball game comprising a plurality of keys covering the results of plays that might be attempted from any formation or situation under foot ball rules, a register for arriving at the proper key following the choice of formation and play, said register including a plurality of dials designated in such manner as to produce a combination covering each formation and play, chance means controlling the results of each play and a 75 80 diagram of a foot ball field including means thereon for indicating the position of the ball at all times.

In testimony whereof, I have hereunto affixed my signature.

VIRGIL C. HARKRADER.
